UNITED STATES PATENT OFFICE.

JOHN H. WHISSEMORE, OF YOUNGSTOWN, OHIO.

DESIGN FOR A HAT AND COAT RACK.

SPECIFICATION forming part of Design No. 19,169, dated June 18, 1889.

Application filed December 12, 1888. Serial No. 293,413. Term of patent 7 years.

To all whom it may concern:

- Be it known that I, JOHN H. WHISSEMORE, a citizen of the United States, residing at Youngstown, in the county of Mahoning and State of Ohio, have invented and produced a new and original Design for a Hat and Coat Rack, of which the following is a specification, reference being had to the accompanying drawing, forming part thereof.
- 5 The figure of drawing is a perspective view of the hat and coat rack, showing the design. The leading features of my design consist of the base, in shape that of two intersecting circles, with a superstructure on the face thereof in shape that of two ellipses joined in line with their shorter axes.
- 10 A A are the two circular portions of the base, and B B are offsets at the point of intersection.
- 15 C C are elliptical frames joined in line with one of their shorter axes by a piece D. The

exterior of each ellipse C has its contour broken by enlargements E, from which spring arms F. These arms project outward, as shown, and terminate in knobs G.

25

What I claim is—

The design for a hat and coat rack herein described and shown, consisting of a base in shape that of two intersecting circles, a superstructure on the face of the base and in shape 30 that of two ellipses joined in line with their shorter axes and having their contour broken by enlargements, and outwardly-projecting arms springing from said enlargements and terminating in knobs, substantially as described.

35 In testimony whereof I hereunto affix my signature in the presence of two witnesses.

JOHN H. WHISSEMORE.
